UNITED STATES PATENT OFFICE.

MORRIS WHITE, OF NEW YORK, N. Y.

DESIGN FOR LEATHER.

Application filed August 18, 1924. Serial No. 10,472. Term of patent 3½ years.

To all whom it may concern:

Be it known that I, MORRIS WHITE, a citizen of the United States, residing at New York city, in the county of New York and State of New York, have invented a new, original, and ornamental Design for Leather, of which the following is a specification, reference being had to the accompanying drawing, forming a part thereof, the figure of which is a plan view of a piece of leather

embodying my new design, the design illustrated in full lines being continued throughout the length and width of the leather.

I claim:

The ornamental design for leather, as shown.

MORRIS WHITE.
